UNITED STATES PATENT OFFICE.

JOSEPH FREDRICK SCHULTHEISS, OF NORTH PLAINFIELD, NEW JERSEY.

SINK-TRAP PROTECTOR.

SPECIFICATION forming part of Letters Patent No. 627,016, dated June 13, 1899.

Application filed March 29, 1899. Serial No. 710,953. (No model.)

To all whom it may concern:

Be it known that I, JOSEPH FREDRICK SCHULTHEISS, a citizen of the United States, residing at North Plainfield, in the county of Union and State of New Jersey, have invented certain new and useful Improvements in Sink-Trap Protectors; and I do declare the following to be a full, clear, and exact description of the invention, such as will enable others skilled in the art to which it appertains to make and use the same.

My invention relates to improvements in sink-valves, and more particularly to that class of sink stench-protectors which are intended to prevent the sewer-gas from passing backward through the sink; and the object is to provide a simple, inexpensive, and effective device of this character.

To these ends the invention consists in certain features of construction and combination of parts, which will be hereinafter more fully described and claimed.

In the accompanying drawings the same reference characters indicate the same parts of the invention.

Figure 1 is a perspective view of my improved stench-preventer valve as it appears applied to a kitchen-sink. Fig. 2 is a longitudinal section of the same.

1 denotes a hemispherical float formed with a flat bottom 2, provided with a serrated flange 3, in which is secured a rubber disk 4 of a size corresponding to the sink strainer-plate, as shown.

5 denotes a tubular guide-stem closed at its top and extending vertically through the rubber washer 4, the bottom 2, and the float 1, the lower end of the tube extending through the strainer-plate to permit the device to

rise and fall by the action of the water in the sink.

When the device is at rest, the rubber washer rests on the strainer-plate and forms a valve to close the same and effectually prevents any foul gases from backing up from the sewer through the sink into the room.

When waste water is run into the sink, it raises the float and escapes and the float falls again and seals the outlet.

When it is desired to fill the sink with water, which may be necessary at times, a detachable weight 6 is slipped over the upper end of the stem 5 to counteract the tendency of the float.

The accompanying drawings show my invention in the best form now known to me; but many changes in the details might be made within the skill of a good mechanic without departing from the spirit of my invention as set forth in the claim at the end of this specification.

Having thus fully described my invention, what I claim, and desire to secure by Letters Patent, is—

The float 1 formed with the bottom 2 and 65 provided with a serrated or toothed flange 3, a rubber disk 4 secured therein, the vertical stem 5, secured in said float, and an independent weight adapted to overcome the buoyancy of said float, substantially as shown 70 and described.

In testimony whereof I have hereunto set my hand in presence of two subscribing witnesses.

JOSEPH FREDRICK SCHULTHEISS.
